UNITED STATES PATENT OFFICE.

HARRY C. ARNOLD, OF MALDEN, MASSACHUSETTS.

DESIGN FOR A TIRE.

47,944.

Specification for Design.

Patented Oct. 12, 1915.

Application filed June 9, 1915. Serial No. 33,195. Term of patent 14 years.

To all whom it may concern:

Be it known that I, HARRY C. ARNOLD, a citizen of the United States, and a resident of Malden, county of Middlesex, and State of Massachusetts, (whose post-office address is Malden, Massachusetts,) have invented a new, original, and ornamental Design for Tires, of which the following description, in connection with the accompanying drawings, is a specification.

In the drawing Figure 1 is a perspective view of a tire showing the design, and Fig. 2 is a sectional view illustrative of the design

which extends throughout the circumference of the tire.

What I claim is:

The ornamental design for a tire, as shown.

In testimony whereof, I have signed my name to this specification, in the presence of two subscribing witnesses.

HARRY C. ARNOLD.

Witnesses:

HENRY T. WILLIAMS,
ROBERT H. KAMMLER.
